HAIRBRUSH

Murray Schotland, New York, N. Y.

Application July 15, 1953, Serial No. 25,962

Term of patent 14 years

(Cl. D86—10)

To all whom it may concern:

Be it known that I, Murray Schotland, a citizen of the United States, residing in New York city, in the county of New York and State of New York, have invented a new, original, and ornamental Design for a Hairbrush, of which the following is a specification, reference being had to the accompanying drawing, forming part thereof.

Fig. 1 is a top view of a hairbrush, showing my new design.

Fig. 2 is a side view of the hairbrush shown in Fig. 1.

Fig. 3 is a bottom view of the hairbrush shown in Figs. 1 and 2.

Fig. 4 is an end view thereof, and

Fig. 5 is a sectional view of the hairbrush taken on line 5—5 of Fig. 1.

The design is characterized by the handle portion thereof.

I claim:

The ornamental design for a hairbrush, substantially as shown and described.

MURRAY SCHOTLAND.
